CLAIM

The ornamental design for a case for electronic device, as shown and described.

DESCRIPTION

FIG. 1 is a rear-perspective view of a case for electronic device, showing my new design;

FIG. 2 is a front-perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The characteristic feature of the design resides in the case for electronic devices having recessed portions respectively formed on top and bottom of a back of the case wherein each recessed portion has a stylish pattern. The recessed portions on the back of the case for electronic device include textured surfaces forming an ornamental pattern that is part of claimed design.

The dashed broken lines in the drawings depict portions of the case for electronic device that form no part of the claimed design. The dot-dash lines define bounds of the claimed design and form no part thereof.

1 Claim, 8 Drawing Sheets
